MACHINE FOR STRETCHING HAT BLANKS

George W. Cuming, New York, N. Y., assignor to
 M. A. Cuming & Co., Inc., New York, N. Y., a
 corporation of New York

Application February 18, 1933, Serial No. 657,395

11 Claims. (Cl. 223—33)

This invention relates to a machine for stretching hat blanks, and an object of the invention is to provide a simple, practical and efficient machine which may be employed for the quick, easy and convenient stretching of hat blanks from their crude initial shapes into shapes suitable for expeditious and proper shaping in other machines to which the blanks are passed after being operated upon by the present machine.

10 A further object is to provide a machine which will include a stretching head over which the hat blank may be drawn and held by hand during the stretching operation.

A further object is to so construct the machine 15 that the stretching operation may be performed partly by the hands of the operator and partly as the result of pressure applied and controlled by means of a foot lever or the like.

20 A further object is to so construct the machine that it will include means to apply steam to the hat blank during the stretching operation.

A further object is to so construct the machine 25 that the supply of steam will be under the convenient control by the operator through the medium of a foot lever preferably associated with the blank stretching foot lever.

A further object is to so construct the machine that the stretching of the hat blank will be uniform in all radial directions.

30 A further object is to so construct the machine that the shape of the stretching head thereof may be altered at will.

Other objects and aims of the invention, more or less specific than those referred to above, will 35 be in part obvious and in part pointed out in the course of the following description of the elements, combinations, arrangements of parts and applications of principles constituting the invention; and the scope of protection contemplated 40 will be indicated in the appended claims.

In the accompanying drawings which are to be 45 taken as a part of this specification, and in which I have shown merely a preferred form of embodiment of the invention:

Fig. 1 is a side elevational view of a machine 50 constructed in accordance with this invention and showing a hat blank in dotted lines as it appears in position over the stretching head of the machine.

Fig. 2 is a vertical sectional view substantially upon the plane of line II—II of Fig. 1.

Fig. 3 is a horizontal sectional view upon the 55 plane of line III—III of Fig. 2 and looking in the direction of the arrows, and

Fig. 4 is a horizontal sectional view upon the

plane of line IV—IV of Fig. 2 and looking in the direction of the arrows.

Referring to the drawings for describing in detail the structure which is illustrated therein, the reference character 1 indicates a main frame including a top or platform portion 1 and suitable legs 2—2 for supporting the platform 1 spaced a suitable distance above the floor 3.

5 Mounted centrally upon the upper surface of the platform 1 is a short pedestal G at the upper end of which is carried the stretching head H.

The stretching head illustrated in the drawings consists of a plurality of separate segments as 4—4 collectively of a generally inverted semi-spherical contour, though it will be understood 15 that this head may be of any appropriate shape according to the shape desired for the completed hat blank.

The segments 4—4 are detachably mounted respectively upon carriers 5—5 which are in turn 20 pivotally mounted as at 6—6 between suitable ears 7—7 formed in pairs at the upper end portion of the pedestal G.

The pivotal mountings 6—6 are disposed circumferentially equi-distant about the central vertical axis of the pedestal, as most clearly indicated in Fig. 3, so that the several segments are 25 free to swing toward and away from each other about their respective pivots, as indicated by dotted lines in Fig. 2.

30 When the several segments are in their closed positions they complete a proper form to initially receive the hat blank thereover, as indicated by the dot and dash line in Fig. 1, and when they are swung outwardly from this closed position 35 they operate to stretch the hat blank radially, the lower edge portion of the blank being mean-while held by the operator's hands as indicated.

The manner of detachably connecting the segments 4—4 with their carriers 5—5 may take any 40 desired form, but in the instance illustrated the segments are merely detachably bolted to said carrier as by means of the bolts 8—8 illustrated which extend through the upper wall of the carrier and engage within threaded apertures provided in the lower wall portions of the segments, respectively. Whenever it is desired to substitute a different shape of stretching head it is merely necessary to remove the bolts 8 and return them again for holding the substitute head 45 segments upon the carriers.

The means employed for swinging the head segments 4—4 may take any desired form, but that illustrated includes a plurality of draw rods as 50 9—9 pivotally connected at their upper ends as 55

at 10—10 with the carriers 5—5 respectively at points radially outwardly from the pivot 6, and being connected at their lower ends as at 11—11 with a plate 12 which is mounted upon a central draw rod 13, the latter extending into pivotal connection as at 14 with a foot lever 15.

The foot lever 15 is pivotally mounted by one end as at 16 upon the frame L and has its opposite end projecting and formed with a suitable foot receiving treadle portion 17 by which the lever may be depressed at the will of the operator; Depression of the lever 15 causes all of the rods 9 to move downwardly in unison and to swing apart the segments 4 accordingly.

15 A tension spring 18 is fixed to the upper end of the central draw rod 13 and has its opposite end fixed as at 19 so that said spring operates at all times to urge the plate 12 and hence the rods 9, upwardly for holding the segments 4 normally.
20 in closed position.

Suitable means may be employed for providing adjustment of the several parts present. In the structure illustrated for instance the rod 13 is longitudinally adjustable as by means of the threaded extension piece 20 thereon, so as thereby to provide adjustment of the tension of spring 18. Also, the plate 12 is adjustable longitudinally of the rod 13, as by means of the oppositely positioned holding nuts 21 and 22 threaded upon said rod and engaging the upper and lower surfaces respectively of the plate, thereby to adjustably move all of the segments 4-4, as may be desired. Also, the length of the respective rods 9 is adjustable as by means of the threaded extension pieces 23-23 at the ends thereof, these pieces permitting of adjustment of the position of the several segments 4-4 with respect to each other, and said pieces 23, as well as the extension piece 20, providing convenient means of pivotal mounting of said pieces as illustrated.

Means is provided for supplying steam within the stretching head H. This means may take any desired form or it may include any preferred construction of parts, but in the instance herein illustrated it consists of a steam jet 24 mounted within the head H, being screwed into the upper end of a central cavity 25 provided in the pedestal G and having one or more outlet openings as 26 by which steam from the cavity 25 may flow into the interior of the head H.

A feed pipe 27 communicates with the cavity 25 through a suitable opening as at 28, and this feed pipe is fitted with a valve 29 which is normally closed but which is adapted to be manually operated into open position whenever steam is desired within the head H.

The valve stem as 30 is normally forced upwardly into valve closing position, by suitable spring mechanism within the valve, not illustrated, and a lever 31 is arranged for engaging the upper end of this stem operable to press the stem downwardly whenever steam is desired.

The lever 31 is pivotally mounted by one end as at 32 adjacent to the stem 30, and its other end is engaged by a link 33 which extends downwardly into pivotal engagement with an auxiliary foot lever 35.

The foot lever 35 is pivotally mounted, preferably upon the lever 15 as by the pivot member 14, and its free end is formed with a foot receiving treadle portion 36 disposed adjacent to the treadle portion 17 and by which the lever 35 may be pressed downwardly to open the valve 29 at any time.

75 It is noted that the foot treadle portion 36 may

stand directly, or partially, above the foot treadle portion 17, so that the operator in pressing down the treadle 36 will, by the same foot movement, press down also the treadle 17 after the treadle 36 has reached the horizontal plane of the treadle 17. The depression of the lever 35 by the treadle 36 whereby the steam valve 29 will be opened, also causes the depression of the lever 15 whereby the segments constituting the stretching head are moved to form openings therein so that steam is admitted to the head during the opening of the segments. If the treadle 36 overlies all or any portion of the treadle 17 the downward movement of the treadle 36 beyond a given point will positively require the treadle 17 to begin downward movement with it, while if the treadle 36 is slightly to one side of the vertical plane of the treadle 17 the operator's foot may if desired project from the treadle 36 so as to engage and press down the treadle 36 whenever the treadle 36 is moved downwardly beyond the plane of the treadle 17. In any event the treadle 36 may be moved downwardly to the horizontal plane of the treadle 17 for thereby admitting steam into the head H at any time and for any period regardless of whether or not the treadle 17 is pressed downwardly.

Usually, in practice, however, the operator presses down the treadle 36 until it meets the treadle 17, thereby admitting the steam into the head H, and he then continues downward movement of both treadles to effect the stretching movement of the segments of the head while a supply of steam is still being admitted into the head.

The steam within the head not only heats the material of the segments of the head, and thereby heats the hat material being stretched, but it also flows outwardly into direct contact with the material of the hat blank thereby moistening and further heating said material, this being highly desirable in order that a quick and proper stretching of the hat material can be effected.

The steam from within the head may find its way outwardly of the head into engagement with the material of the hat blank through the cracks between the head sections, but if desired the segments may be provided with suitable steam outlet apertures therethrough as 31-31. 45

Water of condensation may be conveniently collected and drawn off from the bottom of the cavity 25 as by means of a pipe 38 at the outer end of which is a valve controlled drain outlet 39 disposed in an out of the way position at one side of the machine.

The mechanism as herein shown and described is simple, practical, substantial and highly efficient for its purpose. To use it, an operator merely takes an ordinary hat blank in his two hands and draws it down over the head H after the manner graphically illustrated in Fig. 1. While thus drawing the blank over the head he presses down the foot treadle 36 to admit steam into the head and into contact with the material of the blank, and he continues the downward movement of his foot to move the treadle 17 down for forcing the head segments apart in their respective radial directions. The force with which the head sections move apart is tempered and controlled by the operator's foot and the effect upon the hat blank is at the same time controlled by manipulation of the blank in the operator's two hands. By slightly varying the direction and the strength of the down pull by the hands at different intervals, meanwhile re-

peatedly forcing apart and releasing the head sections to a greater or less extent, while maintaining the flow of steam more or less constant, the hat blank will be readily transformed from its original crude pyramidal shape into a shape more suitably adapted to final shaping in a hat finishing machine. The hat blank is at no time fastened in position upon the machine, but is always carried and handled in the operator's hands from the moment he receives it until he has completed his operation upon it and has passed it on for completion by a hat finishing machine, and thus the stretching and shaping of the hat blank out of its original crude condition may be performed most expeditiously and at small cost.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A machine for stretching hat blanks comprising a head over which a hat blank may be drawn, said head comprising a plurality of sections movable relative to each other for stretching the hat blank, a foot treadle depressible to move said sections, a steam supply for supplying steam into contact with the hat blank, and a second foot treadle mounted above the first foot treadle and depressible to the level of the first foot treadle and further depressible with the first foot treadle, thereby to effect admission of the steam to the hat blank prior to the stretching operation and to continue admission of the steam during the stretching operation.

2. A machine for stretching hat blanks comprising a head over which a hat blank may be drawn, said head comprising a plurality of segments mounted to move in different radial directions with respect to a common center, control means for so moving said segments, and means connected to be operated by said control means for supplying steam into said head during the movement of said segments.

3. A machine for stretching hat blanks comprising a head over which a hat blank may be drawn, said head comprising a plurality of segments mounted to move in different radial directions with respect to a common center, means to admit steam into said head including a movable lever, and other means movable to thereby move said segments said other means being disposed in the path of movement of said lever so as to be moved by movement of said lever.

4. A machine for stretching hat blanks comprising a head over which a hat blank may be drawn, said head comprising a plurality of sections movable relative to each other for stretching the hat blank, carrying means for said head by which said head is supported in position to receive a hat blank drawn downwardly about said head, means manually controllable to move said sections toward and away from each other, said sections and said carrying means co-operating to define a steam cavity between them, and said carrying means having a steam admission passage therethrough through which steam may be fed into said cavity for contact with the hat blank during movement of the sections, and means whereby steam may be caused to flow

through said passage and into said cavity incident to movement of the sections.

5. A machine for stretching hat blanks comprising a head over which a hat blank may be drawn, said head comprising a plurality of segments pivotally mounted to swing apart in different radial directions with respect to a common center, a plurality of rods pivotally connected one with each of said segments for swinging said segments respectively, a plate to which said rods collectively are pivotally connected, a spring connected with said plate for urging said plate and said rods in a direction to swing said segments toward said common center, and a lever connected with said plate operable to move said plate and rods against the tension of said spring to swing said segments away from said common center, together with means by which to at once adjust the tension of said spring and also the position of said plate with respect to said lever.

6. A machine for stretching hat blanks comprising a head over which a hat blank may be drawn, said head comprising a plurality of segments pivotally mounted to swing apart in different radial directions with respect to a common center, a plurality of rods pivotally connected one with each of said segments for swinging said segments respectively, a plate to which said rods collectively are pivotally connected, a spring connected with said plate for urging said plate and said rods in a direction to swing said segments toward said common center, and a lever connected with said plate operable to move said plate and rods against the urge of said spring to swing said segments away from said common center, a steam supply for supplying steam to the hat blank being treated, and a control for said steam supply including a lever extending to a position above the first lever and depressible first into engagement with said first lever and later depressible in common with said first lever.

7. A machine for stretching hat blanks comprising a head over which a hat blank may be drawn, said head comprising a plurality of sections normally abutting edge to edge but being movable relative to each other out of abutting relation for stretching the hat blank, said sections collectively defining a steam cavity between them having steam outlets between the abutting edges of said sections which enlarge as the sections move apart, means for so moving said sections, and means to supply steam into said cavity for contact with the hat blank through said outlets.

8. A machine for stretching hat blanks comprising a head over which a hat blank may be drawn, said head comprising a plurality of segments mounted for movement toward and away from a common center, a lever by which to so move said segments, a steam supply for supplying steam to the hat blank on said head, and a control for said steam supply including an operating member operatively associated with said lever so that operation thereof will operate said lever to move said segments.

9. A machine for stretching hat blanks comprising a head over which a hat blank may be drawn, said head comprising a plurality of sections normally abutting edge to edge but being movable relative to each other out of abutting relation for stretching the hat blank, said sections collectively defining a steam cavity between them having steam outlets between the abutting edges of said sections which enlarge as the sections move apart, means for so moving said sections, and

means to insure a supply of steam within said cavity incident to moving apart of the sections.

10. A machine for stretching hat blanks comprising a head over which a hat blank may be drawn, said head comprising a plurality of sections normally abutting edge to edge but being movable relative to each other out of abutting relation for stretching the hat blank, said sections collectively defining a steam cavity between them having steam outlets between the abutting edges of said sections which enlarge as the sections move apart, means for so moving said sections, and means whereby movement of said sections apart will produce a supply of steam within said cavity for movement through said outlets.

11. A machine for stretching hat blanks com-

prising a head over which a hat blank may be drawn, said head comprising a plurality of segments pivotally mounted to swing apart in different radial directions with respect to a common center, an upstanding pedestal at the upper end of which said head is disposed in position to receive a hat blank held by hand and drawn downwardly about said head, means manually operable to swing said segments toward and away from each other, said segments and pedestal co-operating to define a steam cavity between them, and means connected to be operated by said segment swinging means to supply steam into said cavity for contact with the hat blank during swinging of the segments.

GEORGE W. CUMING.
